US00D821897S

(12) **United States Design Patent** (10) **Patent No.:** **US D821,897 S**
(45) **Date of Patent:** **** Jul. 3, 2018**

(54) **THERMOSTAT**

(71) Applicant: **Johnson Controls Technology Company**, Plymouth, MI (US)

(72) Inventors: **Sudhi Sinha**, Milwaukee, WI (US); **Joseph R. Ribbich**, Waukesha, WI (US); **Michael L. Ribbich**, Columbia, SC (US); **Charles J. Gaidish**, Saint Francis, WI (US); **John Peter Cipolla**, Inverness, IL (US); **Amit Verma**, Sunrise, FL (US); **Vinosh C. Diptee**, Boynton Beach, FL (US); **Hao A. Nguyen**, Lake Worth, FL (US); **Julio A. Abdala**, SW Ranches, FL (US); **Juan Guillermo Alvarez**, Weston, FL (US); **Felippe M. Bicudo**, Fort Lauderdale, FL (US); **Patricia Ellis Douglass**, Pompano Beach, FL (US); **Claudio Santiago Ribeiro**, Evanston, IL (US)

(73) Assignee: **Johnson Controls Technology Company**, Auburn Hills, MI (US)

(**) Term: **15 Years**

(21) Appl. No.: **29/608,761**

(22) Filed: **Jun. 26, 2017**

(57) **CLAIM**

We claim the ornamental design for a thermostat, as shown and described.

DESCRIPTION

FIG. 1 is a front perspective view from above of the claimed design according to one embodiment;

FIG. 2 is a front side view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; FIG. 6 is a top view of the claimed design of FIG. 1; and, FIG. 7 is a bottom view of the claimed design of FIG. 1. The broken lines in the drawings form no part of the claimed design. Lines having a jagged element show that no particular length of the portion is claimed, such lines and any portion of the article between such lines form no part of the claimed design.

1 Claim, 7 Drawing Sheets
